CUP OR SIMILAR ARTICLE

Walfred M. Nyman, Cumberland, R.I., assignor to Nyman Manufacturing Company, Providence, R.I., a corporation of Rhode Island

Filed June 12, 1961, Ser. No. 65,557

Term of patent 14 years

(Cl. D44—9)

FIG. 1 is a perspective view of a cup or similar article showing my new design;

FIG. 2 is a top plan view thereof, it being understood that the fluted pattern shown in the upper right quarter is continuous about the entire circumference in the path indicated;

FIG. 3 is a bottom plan view thereof, it being understood that the fluted pattern shown in the upper right quarter is continuous about the entire circumference in the path indicated; and

FIG. 4 is an enlarged fragmentary elevational view, partly in section.

I claim:

The ornamental design for a cup or similar article, as shown.
